FIXTURE FOR DISPLAYING YARD GOODS
Ralph Meyer, Park Forest, Ill., assignor to Skyline Manufacturing Co., Chicago Heights, Ill., a corporation of Illinois

Filed Aug. 14, 1963, Ser. No. 302,160
7 Claims. (Cl. 108—13)

The present invention relates to a novel display fixture, and more specifically to a novel fixture of the type suitable for displaying merchandise in a store.

While various uses for fixtures incorporating features of the present invention will suggest themselves, such fixtures are particularly suitable for use in displaying and selling yard goods. As will be understood by those familiar with the art, stores selling yard goods usually maintain a substantial inventory comprising many bolts of cloth. In order to display the material, it is sometimes desirable to lay the bolts out horizontally on a table and at other times it is desirable to stand the bolts in a substantially upright position. Such displays provide different requirements for display fixtures.

The bolts of cloth to be displayed frequently are of different widths and in such situations difficulties are encountered in providing a neat and pleasing display. It is apparent that when bolts of different widths are placed in an upright position on a given fixture surface the upper end of the bolts will be at different heights so that a ragged appearing display is provided.

It is an important object of the present invention to provide a novel fixture for displaying and merchandising products such as yard goods and the like, which fixture may selectively be adapted for supporting and displaying goods such as bolts of cloth in a generally upright position and for presenting a generally horizontal surface usable as a display surface or a cutting table or the like.

A further important object of the present invention is to provide a novel display fixture for supporting goods such as bolts of cloth and the like of different widths in a manner such that upper ends of the bolts are at substantially the same height whereby to present a neat and pleasing appearance.

Still another object of the present invention is to provide a novel display fixture for supporting bolts of cloth and the like in a generally upright position in a manner such that the bolts may be quickly and easily removed from or placed on the fixture.

Still another object of the present invention is to provide a novel fixture of the above-described type which is constructed so that bolts of cloth supported in a generally upright position may be easily adjusted in a compact neat appearing display when one or more of the bolts are removed from the fixture or, in other words, when the number of bolts on the fixture is less than the capacity of the fixture.

A more specific object of the present invention is to provide a novel fixture of the above-described type which can be quickly and easily adjusted so as selectively to provide a generally horizontal table top surface or means for supporting bolts in a generally upright position.

A further specific object of the present invention is to provide a novel fixture of the above-described type which may be quickly and easily adjusted for accommodating bolts of cloth of different widths and supporting such bolts in a generally upright position with upper ends of the bolts at a predetermined level.

Still another object of the present invention is to provide a novel fixture of the above-described type which is of simple and rugged construction and which provides a pleasing appearance.

2

A further object of the present invention is to provide a novel fixture of the above-described type which is constructed so that it may be shipped to a customer in a knocked-down condition and then readily assembled by the customer.

Other objects and advantages of the present invention will become apparent from the following description and accompanying drawings wherein:

FIG. 1 is a perspective view showing a fixture incorporating features of the present invention in an adjusted condition for supporting and displaying bolts of material or the like in a generally upright position.

FIG. 2 is a cross-sectional view taken along line 2—2 in FIG. 1.

FIG. 3 is a cross-sectional view similar to FIG. 2 but showing the fixture adjusted for providing a flat horizontal table top surface.

FIG. 4 is an enlarged perspective view of a combined shelf and table top subassembly included in the fixture of the present invention.

FIG. 5 is an enlarged fragmentary sectional view taken along line 5—5 in FIG. 3.

FIG. 6 is an enlarged fragmentary perspective view showing a portion of the shelf-supporting means incorporated in the fixture of the present invention; and

FIG. 7 is an enlarged fragmentary perspective view showing another portion of the shelf and table top supporting means incorporated in the fixture of the present invention.

Referring now more specifically to the drawings wherein like parts are designated by the same numerals of the various figures, a fixture 10 incorporating features of the present invention is shown in FIG. 1. In the condition shown in FIGS. 1 and 2 the fixture is adapted to support a plurality of bolts 12 of fabric or the like in a generally upright position. Alternatively, the fixture 10 is adapted to be adjusted for providing a substantially horizontal table top surface as shown in FIG. 3.

The fixture 10 comprises upstanding opposite end panels 14 and 16 formed from wood, fiberboard or any other suitable material. A base member or bottom shelf 18 extends between lower margins of the end panels 14 and 16. As shown in FIGS. 1, 2 and 3, the base or bottom shelf member 18 preferably has a width for substantially traversing the entire lower marginal edges of the end panels. A generally centrally located upstanding divider panel 20 also extends between the opposite end panels 14 and 16 and rests on top of the bottom shelf 18. Legs 22 are secured to and depend from the four corner portions of the rectangular base member 18 for supporting the fixture on the floor.

In order to facilitate shipment of the fixture in a knocked-down condition and subsequent assembly of the fixture by the customer, the legs 22 are detachably connected with the base member 18 and the base member 18 and the divider panel 20 are detachably connected with the opposite end members. At the same time the construction is such that final assembly of the parts will result in a strong and rigid structure. In this connection it is to be noted that blocks 24 and 26 are secured to a lower marginal portion of the end member 16 but above the bottom edge thereof. The bottom edge of the end member 16 is notched as shown at 28 in FIG. 5 and the notch and the blocks 24 and 26 provide a substantial downwardly facing abutment surface 30 adapted to overlie and fit against the base member 18. Screws 32 are inserted through the blocks 24 and 26 for securing the base member with respect to the end panel 16.

The base member is secured to the end panel 14 in an identical manner. Thus it is not necessary to show the connection between the base member and the end panel 14

in detail and it suffices to state that the lower edge of the end member 14 is provided with a notch identical to the notch 28 and block members 34 and 35 corresponding to the blocks 24 and 26, are secured to the end member 14.

In order to secure the divider panel 20 in position a slot 36 is provided in the upper surface of the base member 18 for receiving a lower edge of the panel 20 and a slot 38 is formed in the end member 16 for receiving an end of the panel 20. A slot identical to the slot 38 is formed in the end panel 14 for receiving an opposite end of the divider panel 20. A plurality of screws 40 spaced along the base member 18 serve to secure the lower edge of the divider panel 20 to the base member 18. In addition an upstanding block 42 is fixed to the end panel 16 at one side of the slot 38 and additional screws 44 are inserted through the block 42 and into the panel 20. Another block 46 is secured to the end panel 14 and corresponds to the block 42 except that it is located at a side of the divider panel 20 opposite from the block 42 whereby to facilitate assembly of the structure. Additional screws, not shown, extend through the block 46 and into the panel 20.

In accordance with an important feature of the present invention the fixture 10 is provided with combined shelf and table top assemblies or units 48 and 50 which, as previously indicated, are adapted selectively to be positioned for supporting the bolts of fabric in generally upright positions and for presenting a generally horizontal table top. The assemblies 48 and 50 are identical and each includes a shelf member 52 and a table top member 54 preferably disposed substantially at right angles with respect to the shelf member. The table top member 54 is secured by suitable means such as adhesives or screws to an edge of the shelf member 52 and is positioned so that a marginal portion 56 of the member 54 extends slightly beyond the bottom surface of the shelf member 52 for the purpose described below. Notches 58 and 60 are formed in opposite ends of the shelf member 52 immediately adjacent the member 54 also for a purpose mentioned below and a reinforcing and divider element 62 is disposed within the angle formed by the members 52 and 54 and is secured to the members.

In order adjustably to support the combined shelf and top units 48 and 50, mounting means 64 and 66 are provided on the end members 14 and 16. The mounting means 64 and 66 are identical so that only the means 64 need be shown and described in detail. In order to support the units 48 and 50 in the position shown in FIGS. 1 and 2 for retaining bolts of material substantially upright, the means 64 comprises a channel member 68 secured to the inner surface of the end member 16. As shown best in FIG. 7 the channel member 68 comprises flanges 70 and 72 defining a slot 74 therebetween. The slot is adapted slidably to receive a marginal end portion of the top member 54 and the previously described notch 58 in the edge of the shelf member 52 provides clearance for accommodating the flange 72 of the channel member. It is to be noted that the channel member 68 is inclined upwardly and inwardly so as to support the unit 48 in a slightly inclined position as shown best in FIG. 2 whereby the bolt 12 of fabric not only rests on the shelf member 52 but will also lean back against the top member 54. This arrangement enables the bolts of fabric to be easily placed on or removed from the shelf while at the same time the bolts will be retained in a manner which substantially precludes them from being accidentally knocked off of the shelf.

In order to secure the shelf unit 48 at the desired height, the mounting means 64 comprises an elongated bracket member 76 secured to the end panel 16 preferably in generally parallel relationship to the channel member 68. The bracket member 76 is formed from a suitable sheet material such as metal and has a raised central portion 78 with a plurality of vertically spaced apertures or slots 80 therein.

A complementary bracket or hanger element 82 is adjustably connected with the bracket member 76 for engaging beneath and supporting the shelf member 52. The bracket element 82 has an upper generally horizontal leg 84 engageable beneath the shelf member 52, which leg terminates in a flange 86 insertable through a selected aperture 80 and engageable behind the central portion 78 of the bracket member 76. The bracket element 82 also has another leg portion 88 which extends downwardly and inwardly from the leg portion 84 and also terminates in a flange 90 insertable through one of the apertures 80 as shown best in FIG. 6. The arrangement of the apertures 80 and the bracket member 76 is such that the upper flat surface of the bracket element leg portion 84 is substantially parallel to and provides a broad area of engagement for the shelf member 52.

It is to be understood that the height of the shelf unit may be readily varied by adjusting the position of the bracket element 82 along the bracket member 76. Preferably the adjustment is made in accordance with the width 10 of the bolt 12 of fabric material to be displayed and as shown in FIG. 2 the height of the units 48 and 50 may be adjusted relative to each other so that bolts of fabric having different widths supported thereon are positioned with upper ends at substantially the same level whereby to provide a neat and pleasing display. It is understood, of course, that the mounting means 66 on the end panel 14 includes identical bracket and channel members for supporting the shelf and top unit 48.

30. The mounting means 64 includes another channel member 92 which is identical to but oppositely arranged from the channel 68. Cooperable bracket members 94 and 96 identical to the bracket members 76 and 82 are also provided association with the channel 92 for supporting the unit 50 in the shelf position shown in FIG. 2. It is, of course, understood that corresponding channel and bracket members are provided in the mounting means 66 at the opposite end of the fixture structure.

35. The units 48 and 50 are readily assembled with or removed from the channel members 68 and 92 of the mounting means merely by sliding the units upwardly or downwardly with respect to the channel member. When the units 48 and 50 are removed they may be turned and mounted in the table providing position shown in FIGS. 3 and 5. The mounting means 64 includes additional channel members 98 and 100 for slidably receiving ends of the shelf members 52 of the units 48 and 50 when the units are arranged in the table top providing position. Of course, the mounting means 66 also includes additional channel members corresponding to the members 98 and 100.

40. The channel members 98 and 100 are arranged in vertical slightly spaced apart relationship between the channel members 68 and 92 and the spacing is such that when the units 48 and 50 are arranged in the table top providing position, the edges of the marginal portions 56 of the top members 54 substantially abut each other as shown in FIG. 3. The channel members 98 and 100 are identical to the channel member 68 except that the upper end of the channel member 68 and also the upper end of the channel member 92 are beveled and disposed in a common plane with the upper ends of the channel members 98 and 100 so that the upper ends of all the channel members provide horizontal stop or abutment surface means for engaging beneath and supporting the top members 54 of the units 48 and 50.

45. While the preferred embodiment of the present invention has been shown and described herein, it is obvious that many structural details may be changed without departing from the spirit and scope of the appended claims.

50. The invention is claimed as follows:

55. 1. A fixture of the type described comprising opposed upstanding and spaced apart end means, a shelf and top unit extending between said end means, said unit including a shelf member and a top member connected to and

extending angularly with respect to said shelf member, and mounting means on said end means for selectively supporting said unit in first and second positions in which first position said top member extends upwardly from said shelf member and in which second position said top member extends generally horizontally, said mounting means including a generally upstanding channel member on one of said end means for slidably receiving an end margin of said top member when said unit is in said first position.

2. A fixture, as defined in claim 1, wherein said mounting means includes an element selectively positionable at different heights on one of said end means and engageable with said unit for adjustably supporting said unit at different heights.

3. A fixture of the type described comprising opposed upstanding and spaced apart end means, a shelf and top unit extending between said end means, said unit including a shelf member and a top member connected to and angularly disposed with respect to said shelf member, and mounting means on said end means for selectively supporting said units in first and second positions in which first position said top member extends upwardly from said shelf member and in which second position said top member extends generally horizontally, said mounting means including means providing a generally upstanding channel on one of said end means for slidably receiving an end marginal portion of one of said members when said unit is in one of said positions.

4. A fixture, as defined in claim 3, wherein said channel means slidably receives said shelf member when said unit is in said second position.

5. A fixture, as defined in claim 4 which includes another generally upstanding channel means for receiving said top member when said unit is in said first position, said last mentioned channel means being inclined from

the vertical for supporting said top member in a position inclined from the vertical.

5 6. A fixture, as defined in claim 5, which includes a bracket element vertically adjustably mounted on one of said end means for engaging beneath said shelf member and adjustably supporting said unit at different heights.

10 7. A fixture of the type described comprising a pair of upstanding and spaced apart end panel members, a base member extending between and connected with lower marginal portions of said panel members, a pair of shelf and top units extending between said end panel members above said base member, each of said units including a shelf member and a top member connected to and angularly disposed with respect to said shelf member, and mounting means on said end panel members selectively supporting said units in first and second positions in which first position said top members of said units extend upwardly from their respective shelf members and 15 in which second position said top members of said units extend horizontally in a substantially common plane.
